UNITED STATES PATENT OFFICE.

VICTOR E. HAAS, OF TOLEDO, OHIO, ASSIGNOR OF ONE-HALF TO SAMUEL E. STARR, OF TOLEDO, OHIO.

CARBURETER.

1,171,716.

Specification of Letters Patent.

Patented Feb. 15, 1916.

Application filed June 7, 1915. Serial No. 32,641.

To all whom it may concern:

Be it known that I, VICTOR E. HAAS, a citizen of the United States, and a resident of Toledo, in the county of Lucas and State of Ohio, have invented a certain new and useful Carbureter; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to carbureters.

It has for its object to provide a carbureter which will automatically regulate the extent of opening of its inlets according to the consumption. The carbureter may be 20 connected to a suction device such as, an internal combustion engine, whether of the stationary type or non-stationary type, in which case the supply of air and the liquid hydrocarbon will vary according to the suction produced by the engine piston, or the device may be connected to a source which supplies air under pressure greater than atmospheric and to a consuming translating device such as, a stove, furnace, lights, or 25 blowpipe, in which case, the supply of the gasolene will be drawn upon according to the flow of the air through the carbureter, that is, according to the rate that the consuming device draws upon or allows the 35 mixture to be consumed.

A further object of my invention is to provide a means for breaking up any drops of hydrocarbon and causing a thorough mixture of the liquid hydrocarbon and pre- 40 venting gradual local collection of heavy liquids.

The invention may be contained in many forms of constructions, all of which are contemplated in the claims hereinafter ap- 45 pended. I have selected one of such constructions as a type of constructions containing the invention and shall describe it hereinafter and explain the operation thereof.

50 The construction selected is illustrated in the accompanying drawings wherein,

Figure 1 illustrates a vertical section of the carbureter. Fig. 2 illustrates a trans- 55 verse section taken on the line 2—2, indicated in Fig. 1 and Fig. 3 illustrates a sec-

tion of an adjusting means taken on the line 3—3, also indicated in Fig. 1. Fig. 4 is an air valve shown in section in Fig. 1.

10 is the main shell of the carbureter having formed therein three chambers, 11, 12 60 and 13. They are preferably made cylindrical in form for ease of construction and manipulation of parts. The lower end of the shell 10 is covered by a cap 14 forming the chamber 21. The cap is secured by the 65 screws 20 to the shell 10. The chamber 11 is closed by a cap 15, chamber 12 is closed by a cap 16, and chamber 13 is provided with an outlet. The carbureter selected and illustrated in the drawing is provided with the 70 type of outlet pipe which is commonly used for connecting carbureters with internal combustion engines. The outlet pipe 17 is provided with the usual butterfly valve 18 which may be adjusted by means of the arm 75 19 to vary the effective area of the passage-way from the carbureter to the engine through the outlet 17.

The cap 15 of the chamber 11 is provided with an inlet 25 to allow atmospheric air 80 to pass into the carbureter. It may be connected with a pipe which leads from a source of air supply which may be forced under pressure into the carbureter particularly, when the carbureter is used in connection with lighting or heating systems or with a blowpipe. The cap 15 is screwed upon the top of the cylinder 11 and secures between itself and a ring 26 which is formed with a seat 27 and a frustum central re- 85 cess 28, a felt 29 which is supported by means of a perforated disk or sieve 30. The ring 26 may be cast in one piece with the cylinder 35, or the cylinder 35 may be otherwise secured to the ring 26. The cylinder 90 35 depends from the ring 26 into the chamber 11. The lower end of the cylinder 35 is closed with the head or threaded disk 36. A piston 40 having a hollow or flanged piston head of considerably vertical length is located within the cylinder 35 and having ribs 39 to reduce frictional contact. It is provided with a stem 41 which extends through the disk 36. A light compression spring 42 operates to yieldingly hold the 105 piston 40 against the ring 26. The cylinder is provided with slotted openings 43 which are located vertically and are opened by the movements of the pistons 40 to a more or less extent and according to the 110

extent of movement of the piston 40. The cylinder 35 may also be provided with openings 44 to allow free movement of the piston 40. Also, the opening 45 through which the stem 41 extends may be a little larger than the stem 41 in order to permit free movement of the air or gas in and out of the cylinder 35 to permit free movement of the piston 40.

10 The chamber 12 is provided with a sleeve or valve casing 50. Within the casing is located a movable valve member 51 having a cone or needle end 52 which seats upon the seat 53 of the casing 50. The casing 50 is provided with an opening 54 which affords a communication between the chamber 12 and the chamber 21 formed by the cap 14 below the shell 10 when the valve member 51 is removed from its seat 53. A 15 spring 55 is located within the sleeve 50 and about the stem 56 which forms a part of the movable valve member. The spring 55 is a light compression spring and extends between an enlarged portion of the movable valve member 51 and a flexible disk or diaphragm 60 which is secured in position by means of the cap 16 which is threaded into the shell 10. The interior of the 20 chamber 12 may be sealed by means of the lead washer 61 located in a recess 62. A screw 65 is located in the cap 16. One end of the screw 65 presses against the disk or diaphragm 60 at a point opposite to the point at which the compression spring 55 25 presses against the disk 60. The screw 65 may thus be altered to adjust the pressure of the spring 55 against the enlarged portion of the movable valve member and thus 30 adjust the pressure at which the valve member 51 will be forced against its seat 53. Adjustment of the screw 65 thus operates to adjust the force required to lift the valve member 51 from its seat.

The diaphragm 60 permits an adjustment 45 of the spring 55 relative to the pressure that may be exerted by the valve 40 to control the flow of the liquid relative to the air. The diaphragm is also important when it is considered that it is almost impossible to 50 secure an adjustment of the liquid inlet valve of the carburetor without permitting the escape of vapors. The diaphragm completely seals the gasoline chamber of the carburetor. The threaded screw extends 55 through the cap which covers the chamber and presses against the diaphragm, which prevents any gasoline vapors escaping from the chamber through the threads of the adjusting screw. Adjustment can thus easily 60 be produced by the screw when desired without permitting the escape of gasoline vapors.

The shell 12 is provided with an inlet pipe 36 which may be connected to a source 65 of supply of liquid hydrocarbon. The

liquid hydrocarbon enters the chamber 12 through the pipe 36 and thence it passes through the sleeve 50 and opening 54 according to the extent of movement of the valve member 52 which, to a certain extent, 70 is regulated by the pressure of the spring 55. The chamber 12 is provided with a ridge 105 forming a seat on which a disk 106 having holes formed therein is placed. A filter 58 of felt or other suitable material 75 is placed on the disk 106 and the disk 57 is placed above the fibrous material 58. A sleeve 59 is placed on the cylinder 57, on which is supported the diaphragm 60. The parts are secured in position by means of 80 the cap 16.

The valve member 51 is opened by the operation of the piston 40. They are connected together by a suitable mechanical means whereby the valve 51 is lifted according to the extent of movement of the piston 40. The piston 40 moves according to the difference of pressure produced above and below the piston. The piston 40 consequently moves according to the rate of flow 90 of the air or the mixture through the carburetor and consequently according to the consumption of the mixture. In the form of the invention shown, the piston 40 and the movable valve member 51 are connected together by a simple or a compound lever. The stem 41 of the piston 40 is provided with a cross-pin 70 which extends through the forked end 71 of the lever 72. The lever 72 is pivoted on a frame 73. The frame 73 100 is pivoted on the shell 10 by means of the pivot pin 74. A second lever 75 is pivoted on the frame 73 by means of the pivot pin 76. The lever 72 operates on the lever 75 and thus compounds its reduction of movement. The lever 75 operates upon the pin 77 which extends through the opening 54 and lifts the movable valve member 51 when the piston 40 is lowered by the difference of 105 pressure of the air above and below the piston.

The frame 73 is provided with an adjusting screw 80 which is threaded into the shell 10. A compression spring 81 is located about the screw 80 and intermediate the shell 10 and an ear 82 which is secured to the frame 73. The position of the frame 73 may thus be adjusted relative to the shell 10, the screw operating to vary this relationship while the spring 81 operates to hold the ear 82 against the head of the screw 80. As the screw 80 is threaded into or out of the shell 10, the frame 73 is varied in its relation to the shell 10 as it turns about the pivot pin 74. This likewise varies the 115 relationship between the compound lever 72, 75, to the pin 77 of the movable valve member 51 and consequently varies the relation between the piston 40 and the movable valve member 52. As the piston 40 120

is moved down by the difference in the pressure of the air on opposite sides of the piston; the levers operate to open the movable valve member 51 to a more or less extent 5 and allow more or less of the hydrocarbon to enter the chamber 21.

Suitable deflectors 85 may be located on opposite sides of the levers 72 and 75 intermediate the opening 54 and the chamber 11. 10 Preferably the deflectors 85 are located substantially beneath the opening 54. The gasolene which drops on the levers and then to the deflectors, passes through the current of the air which enters the carbureter 15 through the chamber 11 and passes below the deflectors and mixes with or vaporizes the falling liquid.

The chamber 13 is provided with angularly disposed pipes or openings 90 through 20 which the mixed air and liquid hydrocarbon may pass from the interior of the cap 14. The pipes 90 are disposed so as to produce circular or spiral movements of the vapor within the chamber 13. Two of them extend 25 to top of chamber 21 and two extend to near bottom of chamber 21. The chamber 13 is also provided with a means for breaking up the particles of liquid hydrocarbon and producing a thorough mixture 30 of the air and the liquid hydrocarbon that may be carried up into the shell. In the form of the invention shown, the chamber 13 is provided with one or more rotatable combs 91 which beat the fluids as they pass 35 through the chamber. They are supported upon the shaft 92. The shaft 92 is stepped in a bearing 93 located in the lower end of the chamber 13 and also in a bearing pin 94 which is threaded into a bridge 95 secured in the top of the shell 10. The bridge 40 95 may be threaded into the top of the shell and also secured therein by means of the outlet pipe 17 which is also threaded in the top of the shell 10 above the chamber 13. 45 The lower end of the shaft 91 is provided with a propeller 97 whose plates are so tilted as to meet at right angles the impact of the moving vapor as it enters through the openings or pipes 90 located in the bottom 50 of the chamber 13. The vapor thus causes the propeller to rotate the combs 91 and break up the liquid particles insuring thereby a perfect mixture of the vapor of the liquid hydrocarbon and the air. The 55 combs 91 may be provided with teeth which vary in width, the lower teeth being preferably wider than the upper teeth. The lower teeth will thus operate directly on the larger particles of liquid hydrocarbon to break 60 them up while the finer teeth will operate upon the more perfectly vaporized liquid hydrocarbon and at the same time produce a perfect mixture of the vapor and the air as it leaves the chamber 13.

65 In order to give a substantial uniform

rate of rotation to the combs 91 and shaft 92 a body having considerable mass may be secured to the shaft. The wheel 99 having a rim 98 of considerable size is keyed to the shaft 92. The wheel 98 acts like a flywheel to give substantial uniform speed to the combs as they are rotated by the moving vapor which strikes the plates of the propeller 97.

The invention may be greatly modified by 75 those skilled in the art without departing from the spirit of the invention. The construction described is merely illustrative of carbureters containing my invention and wherein advantageous results enabled by 80 my invention are produced.

Having thus described my invention, what I claim as new, and desire to secure by Letters Patent, is,—

1. In a carbureter, the combination of an 85 air valve and a liquid hydrocarbon valve, the liquid hydrocarbon valve operated by the air valve, a pair of levers mechanically connecting the two valves, an adjustable pivoted frame for supporting the levers, one 90 of the levers pivotally supported near the pivot of the frame and the other of the levers pivotally supported at the end of the frame remote from the pivot of the frame.

2. In a carbureter, the combination of a 95 hydrocarbon liquid valve, a compression spring for seating the valve, a metallic diaphragm abutting one end of the spring, an adjustable screw abutting the diaphragm, at a point opposite to and on the opposite side of the point at which the spring abuts the diaphragm, a lever for opening the valve, an air valve for operating the hydrocarbon liquid valve against the operation of the spring, and a chamber for receiving the hydrocarbon liquid and the air. 100

3. In a carbureter, the combination of an air valve having a flange, a sleeve in which the valve moves, having slotted openings, a hydrocarbon liquid valve, a pair of levers 110 connecting the valves for opening the liquid valve, as the air valve is opened, a chamber located beneath the valves for receiving the air and liquid, a mixing chamber, the air passing beneath the inlet of the hydrocarbon liquid and with the hydrocarbon liquid into the mixing chamber. 115

4. In a carbureter, the combination of an air inlet valve and a hydrocarbon liquid valve and a mixing chamber, a communicating chamber for conducting the air beneath the hydrocarbon liquid valve to the mixing chamber, pipes extending to the bottom of the communicating chamber for conducting the liquid hydrocarbon, its vapors and air, 120 into the mixing chamber. 125

5. In a carbureter, the combination of an air inlet valve and a hydrocarbon liquid valve, a pair of levers connecting the valves for opening the liquid valve proportionate 130

to the opening of the air valve, a chamber located beneath the valves for receiving the air and the liquid as they pass through the openings formed by the valves, a deflector 5 for deflecting air current toward the bottom of the chamber.

6. In a carbureter an air inlet valve and a hydro-carbon liquid inlet valve, the carbureter having a chamber extending under 10 the openings of the valves, a deflector disposed in proximity to the hydro-carbon liquid inlet valve to deflect the air downward in advance of the hydro-carbon liquid inlet valve, whereby the air current receives 15 the hydro-carbon liquid as it passes along

underneath the liquid valve opening and the deflector.

7. In a carbureter the combination of an air inlet and a hydro-carbon liquid valve, the carbureter having a chamber for conducting the liquid vapors and the air, a deflector for deflecting the air current to the bottom of the chamber, the chamber having outlets, one outlet at the bottom of the chamber and the other at the top of the 20 25 chamber.

In testimony whereof, I have hereunto signed my name to this specification.

VICTOR E. HAAS.
